UNITED STATES PATENT OFFICE.

EVERETTE G. EARNHARDT, OF BATH, PENNSYLVANIA.

SNOW REMOVER.

Application filed October 23, 1925. Serial No. 64,441.

It is the object of the present invention to provide a device in the nature of a vehicle attachment for removing snow from the street or highway, by melting the snow in an 5 expeditious and economical manner.

In carrying out the invention I contemplate the use of a plurality of burners arranged in a suitable casing supported in advance of the machine, and equipped with a 10 deflector at one end thereof, which is designed to direct the heat forwardly and downwardly to accomplish the desired result.

An object of the invention resides in the provision of means whereby the said casing 15 with its burners can be quickly mounted upon the vehicle, and the casing adjusted with relation to the ground, so that the casing can be properly positioned as conditions may require.

20 The nature and advantages of the invention will be better understood when the following detailed description is read in connection with the accompanying drawings, the invention residing in the construction, combination and arrangement of parts as claimed.

25 In the drawings forming part of this application, like numerals of reference indicate similar parts in the several views, and where-
30 in:

Figure 1 is a side elevation of a vehicle partly in section and showing the invention applied thereto.

35 Figure 2 is a plan view of the casing showing the burners associated therewith and the arrangement of the fuel and air tanks.

Figure 3 is a sectional view through the casing.

40 Figure 4 is a fragmentary perspective view of one end of the casing.

Referring to the drawings in detail, 10 indicates a vehicle of any desired construction upon which the device forming the subject matter of the present invention is adapt-
45 ed to be mounted.

The vehicle is preferably of the motor operated type, and the casing 11 is adapted to be supported from the hood of the vehicle in the manner clearly illustrated in Figure 50 1. In other words, the casing 11 is arranged in advance of the vehicle and is open at its forward end as indicated at 12 in Figure 4, inasmuch as the heat from the burners 13 is adapted to pass from the open end of the

55 casing and utilized to melt the snow on the street or highway over which the vehicle travels, thereby quickly removing the snow, as will be readily understood. Supported by the forward end of the casing 11 is a deflector 14 which may vary in size and configuration, but designed to direct the heat downwardly. As shown in Figure 2, a plurality or series of burners 13 are arranged within this casing and supported by the rear 60 wall thereof, each burner being surrounded by a perforated sleeve 15 to protect the casing from the flame. All of the burners communicate with the branch 16 of a fuel supply pipe, the other branch 17 of which leads from a fuel supply tank 18 adapted to be 70 conveniently located on the vehicle 10, and which tank 18 is supplied with compressed air from an air compressor 19. The communication between the fuel supply pipe and the burners is established by feed pipes 20, 75 there being one of these pipes for each burner, as clearly shown in Figure 2, while the communication between the feed pipes 20 and the burners 13 is controlled by needle valves 21. Supported by each burner direct- 80 ly beneath the perforated sleeve 16 is a cup or receptacle 22 which is employed to initially heat the burners before the machine is put into operation. The branch 17 of the supply pipe includes a flexible section 23 to protect 85 this pipe from injury or breakage incident to the vibrations of the machine. Manifestly, the valves 21 can be properly adjusted to admit the desired quantity of fuel from the tank 18 to the burners, and when the latter 90 are in operation the heat therefrom passes through the casing 11 and is directed downwardly onto the snow by the deflector 14, thereby quickly and economically removing 95 the snow, by causing it to melt, whereupon the water finds its way to the sewers.

For supporting the casing 11 I preferably employ uprights 24 which are arranged at the sides of the hood of the vehicle, rising above the latter and supporting therebetween a drum 25. The drum is mounted for rotation and is provided with a crank handle 26 for this purpose. The uprights 24 are secured to the frame of the vehicle as at 27 and are further braced and supported by 100 bracket strips 28 secured to the hood. Sup- 105 ported by the casing 11 adjacent the rear thereof is a rod 29 which is held spaced

- from the casing by suitable brackets or bearings 30. Connected with this rod are links 31 which project downwardly from the uprights or standards 24, thereby supporting 5 the casing 11 for pivotal movement, so that it can be raised or lowered with relation to the ground, and thereby properly positioned, depending upon the condition of the snow or ice to be removed. Any suitable 10 means may be employed, such as a ratchet mechanism for holding the snow remover in an operative position with relation to the vehicle. A plurality of flexible cables 32 have their corresponding lower extremities 15 secured to the casing 11, while these cables are connected with the drum 25 and adapted to be wound thereabout or unwound therefrom to adjust the casing as the occasion may require.
- 20 While it is believed that from the foregoing description the nature and advantages of the invention will be apparent, I desire to have it understood that I do not limit or confine myself to what is herein shown and described, and that such changes may be resorted to when desired as fall within the 25 scope of what is claimed.

Having thus described the invention, what is claimed as new, is:—

An attachment for automobiles, comprising a pair of spaced parallel upright standards arranged at the opposite sides of the hood of the automobile and projecting thereabove, each standard having its lower portion twisted and formed with a laterally extending portion constituting an attaching foot secured to the frame of the automobile, links pivoted on said standards at points intermediate the ends thereof and projecting downwardly and forwardly therefrom and terminating in advance of the frame of the automobile, a casing pivotally supported by the forward extremities of said links, a drum journaled between the upper ends of the standards, a cable attached to the casing and secured to and wound about said drum, means for rotating the drum, bracing elements extending substantially longitudinally of the hood and connected at their ends with the latter and with said standards at points above the adjacent ends of said links.

In testimony whereof I affix my signature.

EVERETTE G. EARNHARDT.
